UNITED STATES PATENT OFFICE.

HENRY J. EDWARDS, OF ELYRIA, OHIO, ASSIGNOR TO INDUSTRIAL RESEARCH CORPORATION, OF TOLEDO, OHIO, A CORPORATION OF DELAWARE.

AUTOMATIC SPARK AND CHOKE-VALVE CONTROL.

Original application filed November 25, 1918, Serial No. 264,064. Divided and this application filed September 16, 1920. Serial No. 410,634.

This invention relates to improvements in automatic speed regulating devices for internal combustion engines of the type known as sliding sleeve valve or Knight engines illustrated and described in my former application, Serial No. 264,064, filed November 25, 1918, and of which this application is a division.

By my invention I contemplate the use of automatic means for controlling the speed of the engine, including a valve controlling mechanism responsive to the engine speed. The particular arrangement of speed controlling means, the location of the speed responsive device, together with the particular arrangement of a controlling valve, also constitutes one of the novel means which my invention is intended to provide, and in this connection I also provide a manually controlled means for simultaneously varying the mixture delivered to the engine and controlling the spark advance, this feature having particular utility in starting the engine, and, when once operated, is left open and the mechanism thereupon operates automatically.

This invention further contemplates and has for its object the provision of a novel arrangement of fuel and air-mixing valve of a simplified character, avoiding the necessity of the use of a carburetor, the same being also located and arranged so as to draw air from the interior of the crank case of the engine.

Further objects of the invention relate to various economies of manufacture and details of construction as will hereinafter appear from the detailed description of that particular embodiment of the invention which for purposes of illustration I have shown in the appended drawings in which,

Figure I is a side elevation of the engine and the electric generating unit operated by it, viewed from the side on which the timer and inlet pipe are located.

Figure II is an end elevation, viewed from the generator end.

Figure III is a section on line 3—3 of Figure I.

The novel type of air and fuel mixing valve, its combination with the crank casing of the engine, and the automatic control of the speed of the engine by a speed responsive mechanism connected with the throttle of the engine, together with the manually con-

trolled means for varying the combustible mixture will, it is believed, be understood from the following description taken in connection with the drawings.

A hollow casting 80 is made in the form of a Venturi pipe connected at one end to the intake passage 81 of the engine cylinder 1, as appears from Figure III. The fuel contained in the fuel tank 82 is lead to the mixing valve by a pipe 83 which opens into the mixing valve by way of an opening 84 located just preceding the narrowest portion of the Venturi pipe, as appears from an inspection of the drawing. The casting 80 is provided with an upwardly extending projection 86 recessed to receive a filtering material 87 held in place by a suitable apertured plate 88 to form means for priming the engine with gasoline in starting, the casting 80 also having a vertical opening 89 therethrough to connect the interior of the projection 86 with the Venturi passage. It will thus be seen that the Venturi pipe or mixing valve is constantly open to the atmosphere at its most restricted point.

The casting 80 is provided with a downwardly extending terminal 90 which is provided with bearings 91 and 92 for a butterfly valve 93, the valve in turn being provided with a valve handle 94 to be operated manually. An air tube 95 is connected to the lower extremity of the terminal 90, and this tube has adjacent the lower end thereof a plurality of inlet openings 96, whereby it will be seen that air may be drawn in through the pipe 95 and pass the valve 93 when open, through the Venturi pipe in the casting 80 and into the intake manifold 81 to the engine. It will be noted that the openings 96 in the tube 95 communicate directly with the atmosphere. The lower end of the tube 95 is supported by a casting 97, which is joined at its opposite end to the casing 13, as appears from Figure I. The casting 97 is hollow, as indicated and connects with a passage communicating directly with the interior of the crank casing of the engine. Supported on a suitable base ring 100 are a plurality of reeds 101 and 102 adapted to operate as a check valve to permit air to be drawn out through the hollow pipe connection 97 from the interior of the crank casing into and through the pipe 95, and prevent air from returning into the crank case therethrough. It will be noted that the

reeds 101 and 102 may be made relatively delicate and particularly efficient in operation for the purposes intended. When the engine is first started and the piston 59 descends, the same forces the air out of the crank casing 13 and through the passage in the casting 97, past the check valve formed by the reeds 101 and 102, and through the tube 95 whence it is drawn into the intake passage, as will be readily understood from the construction shown and described. Upon this suction stroke of the engine, it will thus be seen that the air is exhausted from within the crank case of the engine and thereafter upon a compression stroke thereof, the reeds 101 and 102 close to prevent the re-entrance of the air to the crank case, and the mechanism operates to tend to provide a partial vacuum within the crank case. It will be seen that this system operates to prevent leakage of oil around the bearings and moreover when used with a Knight engine in which the compression is particularly effective, the system operates to improve the operation of the engine generally.

The mixture controlling valve 93 having the operating handle 94 has connected thereto a lever 105 extending downwardly and linked to an arm 106 extending interiorly of a timer casing 107 to connect and carry a movable arm 108 of the timing mechanism. As shown, the timer 109 is located on and directly operated by the transverse eccentric shaft 40 of the engine. In this manner it will be seen that the mechanism may be arranged to retard the spark and at the same time shut off the air to provide a rich mixture in starting the engine, and that when once started the spark is automatically advanced to the proper timing with the speed of the engine when valve 93 is brought to a position to so regulate the amount of air drawn into the mixing valve as to produce the proper mixture with the fuel used. It is, of course, apparent that the valve 93 may be arranged to be operated separately of any spark controlling means, if desired. It is to be noted that the charge forming device has no adjustable parts whatever, such as needle valve, or auxiliary air valve and hence is incapable of becoming disadjusted when operated by unskilled persons. The use of this non-adjustable charge former is rendered possible by my combination of choke valve and speed governor as described hereinafter.

The mixing valve or casting 80 is provided with a butter-fly throttle 110 as shown in Figure III, and the same may be connected by a system of levers 111 to a speed responsive device regulated by the speed of the engine. In the particular type employed herein, I have chosen to provide the eccentric shaft with a governor 112 having the fly weights 113 pivoted to a collar 113' on the shaft 40, and connected to a sliding sleeve

114, which carries a yoke 115 connected to the rock arm 116 which in turn is pivotally connected to one of the levers 111. The fly weights 113 of the governor being pivoted to a member secured to the shaft 40, it will be seen that as the engine speed increases, the fly weights will be centrifugally flung outwardly and operate to draw the sleeve inward accordingly. The yoke 115 carried by the sleeve, operates to rock the shaft 116 and thus control, through the system of lever connections 111, the position of the throttle valve 110. This forms one way whereby the throttle is controlled by a speed responsive device driven from the engine. To further enhance the constant speed at which the engine operates, I have provided a dash pot 120 connected to the rock shaft 116 to thus further regulate and render more even the actuations of the governor in controlling the speed of the engine. Any suitable dash pot construction for this purpose may be employed, and a detailed description of the one used is, therefore, deemed unnecessary.

While I have described my invention in more or less detail, and as being embodied in certain forms, I do not desire or intend to be limited thereto, as it is obvious to those skilled in the art that my invention is capable of various modifications and arrangements of parts, as defined by the scope of the appended claims.

I claim as my invention:

1. In an internal combustion engine, having a cylinder and a fuel intake passage, the combination of an integral fuel and air mixing device, a throttle valve between the mixing device and engine, an air conduit connected to the mixing device, a choke valve in said conduit, a spark timer for the engine, and single means for operating said choke valve and timer.

2. In an internal combustion engine having a cylinder and a fuel intake passage, the combination of an integral fuel and air mixing device, a speed responsive throttle valve between said mixing device and engine cylinder, an air conduit connected to the mixing device, a choke valve in said conduit, a spark timer for the engine, means for advancing and retarding said timer, and means for simultaneously closing the choke valve and retarding the timer.

3. In an internal combustion engine having a cylinder and a fuel intake passage, the combination of an integral fuel and air mixing device, a speed responsive throttle valve between said mixing device and engine cylinder, a spark timer for said engine, a choke valve for cutting off the main air supply to said mixing device and having interconnection with said timer, whereby during starting the spark is retarded and a rich mixture furnished by the closing of said choke valve, and during normal running a

lean mixture, is furnished by opening said choke valve and the engine speed governed by said throttle.

4. In an internal combustion engine having a cylinder, a fuel intake passage and a crank case, the combination of a fuel and air mixing device; an air conduit between the mixing device and the crank case; a spark timer for the engine; means in said conduit for controlling gas movement from the crank case to said mixing device; and additional single means for operating said timer and gas controlling means.

5. In an internal combustion engine having a crank casing, a cylinder and a fuel inlet passage; the combination of an air control-

ling valve adapted to be connected to the fuel inlet passage; a timer; means to simultaneously operate said timer and air controlling valve; a conduit between said valve and the interior of the crank casing; and a check valve in said conduit, said check valve consisting of flexible leaf members having corresponding ends attached to opposite sides of said conduit and their other ends contacting, and side plates for said members, said leaf members converging in a direction toward the mixing valve whereby said leaf valve is opened only on the movement of air from the crank case.

In testimony whereof, I affix my signature.
HENRY J. EDWARDS.
